 Tony Hom

(57) **CLAIM**

A new, original, ornamental design for an ice/earth driller, as shown and described.

DESCRIPTION

FIG. 1 is a front view of an ice/earth driller showing my new design;

FIG. 2 is a back view thereof;

FIG. 3 is a left view thereof;

FIG. 4 is a right view thereof;

FIG. 5 is a top view thereof;

FIG. 6 is a bottom view thereof; and,

FIG. 7 is a perspective view thereof.

The broken lines in the drawing depict environmental subject matter only and form no part of the claimed design.

1 Claim, 7 Drawing Sheets
